United States Patent Office.

ELHANAN OMENSETTER, OF PHILADELPHIA, PENNSYLVANIA, ASSIGNOR
TO SAMUEL MACFERRAN, OF SAME PLACE.

Design No. 4,195, dated June 28, 1870.

DESIGN FOR IRON RAILING.

The Schedule referred to in these Letters Patent and making part of the same.

I, ELHANAN OMENSETTER, of the city of Philadelphia, and State of Pennsylvania, have invented and produced a new and original Design for Iron Railings, of which the following is a specification.

The nature of my design is fully represented in the accompanying photographic illustration, to which reference is made.

The photograph represents a side elevation of a panel of a fence, composed of longitudinal rails, A A', and open pales B.

The middle portion of the pales B, between the rails A A', is composed of two triplicate curved members, a a' a'', which meet together in the middle, and connect at their upper and lower ends with the upper and lower rails A A'. The middle portions a are elongated.

These members have central openings, b b' b'', corresponding in form to their outside edges.

A double scroll, d, gives finish to the lower end of the pales B, the upper portion of it being of reversed form to the part a' with which it connects.

The upper ends of the pales are continued from the rail A' by a reversed member, a', and heart-shaped member, e, which has a crown leaf, f.

The said pales have wings, g g, which have four-leafed ornaments, h h, that have central buds, j.

The rails A A' have enlargements, g', of like form to the wings g, and similar ornamentation.

The diminished portions k of the rails have ornamental bands l.

I claim as my invention—

The design for iron railing, as shown.

In testimony that the above is my invention, I have hereunto set my hand and affixed my seal this 23d day of April, 1870.

ELHANAN OMENSETTER. [L. s.]
